UNITED STATES PATENT OFFICE.

MICHAEL L. HILLER, OF NEW YORK, N. Y.

METHOD OF ORNAMENTING FABRICS.

SPECIFICATION forming part of Letters Patent No. 399,897, dated March 19, 1889.

Application filed December 5, 1888. Serial No. 292,725. (No model.)

To all whom it may concern:

Be it known that I, MICHAEL L. HILLER, a citizen of the United States, residing at New York, in the county of New York and State 5 of New York, have invented a new and useful Improvement in the Ornamentation of Fabrics, of which the following is a specification.

My invention relates to the ornamentation 10 of fabrics; and it consists in embroidering the surfaces of material in a novel and inexpensive manner, as is herein described, illustrated in the drawings, and specifically pointed out in the claims.

15 Referring to the accompanying drawings, wherein like letters of reference point out similar parts on each figure, Figure 1 represents a shoe-vamp ornamented with a design in beads in the ordinary manner; Fig. 2, a 20 shoe-vamp ornamented with leaves composed of beads springing from stamen or leaders composed of continuous lengths of cord, according to my invention.

In the drawings, A represents continuous 25 lengths of cord sewed upon the surface of material, illustrated as the vamp of a shoe.

a represents leaves composed of a series of beads in a manner well known in the art of ornamenting fabrics.

30 It is customary in analogous devices to form the leaves or flora, as well as the stalks, leaders, or outlines from which leaves, tendrils, or flora extend, by means of separate beaded stitches, as illustrated in Fig. 1. It is obvious 35 that this involves considerable labor and time. The object of my invention is to produce the same general effect at a reduction of labor and expense by composing the stalk or stamina of the general design of one or more 40 continuous lengths of cord, which, when sewed in place, as illustrated in Fig. 2, have the appearance of lines of beaded work.

I herein denominate the stamina A generally as "leaders," including thereby the 45 stalks, outlines, and all characters of lineal

work that compose portions of a general design. By the terms "flora" and "floriform" I include all forms representing leaves, flowers, pistils, tendrils, and those parts of a general design, whether floriform or not, that outlie or spring from the leaders. I do not desire to be understood as limiting myself to the employment of any given design, nor simply to illustrations of plants, flowers, or any description of flora. My invention is equally 55 applicable to arabesque designs or any character of configurative ornamentation having leaders composed of continuous lengths of cord, from which outlie leaves, tendrils, pistils, floriations, or any small bead-work extensions, which, in combination with the leaders A, constitute a given composite design.

For convenience of description I have illustrated my invention as applied to a shoe-vamp, but do not limit myself to its employment 65 thereto, nor to its application to leather only, as it is my intention to utilize it for ornamentation of textile and other fabrics.

Having now fully described my invention, what I claim, and desire to secure by Letters 70 Patent, is—

1. In the art of ornamentation of fabrics, an embroidered surface, the leaders of the design being composed of one or more lengths of cord sewed flatly in place, and having extending from said cord lengths of smaller members of the general design composed of a series of beaded work, substantially as described. 75

2. The within-described means for ornamenting surfaces of fabrics, which consists 80 in the combination of leaders A, formed of lengths of cord sewed in place upon such surfaces, with extensions branched out therefrom composed of series of bead-work, as and for the purpose indicated, substantially as described. 85

MICHAEL L. HILLER.
